FIG. 3.

FIG. 4.

Inventor

Cyrus Kehr

UNITED STATES PATENT OFFICE.

CYRUS KEHR, OF WASHINGTON, DISTRICT OF COLUMBIA.

PRESS.

Application filed April 10, 1922. Serial No. 551,344.

To all whom it may concern:

Be it known that I, CYRUS KEHR, a citizen of the United States, residing at Washington, in the District of Columbia, have invented a new and useful Improvement in Presses, of which the following is a specification, reference being had to the accompanying drawing.

This invention relates particularly to presses containing a series or group of superposed horizontal plates or platens between which sheet-form material is to be placed for pressing, the plates or platens being at times separated to permit the insertion of material between them and being afterwards forced toward each other to engage and press the material.

The object of this invention is to produce a machine embodying effective mechanism for controlling and moving the plates or platens.

In the accompanying drawings.

Fig. 1 is a front elevation of a machine embodying my improvement, parts being broken away;

Fig. 2 is an elevation of one of the ends of the same machine;

Fig. 3 is a plan of the same machine, parts, being broken away;

Fig. 4 is a horizontal section on the line, 4—4, of Fig. 1;

Fig. 5 is a horizontal section on the line, 5—5, of Fig. 1.

Referring to said drawings, A, A are four upright corner posts or columns forming parts of the frame of the machine. These columns are of angle form, as shown in cross section in Figs. 4 and 5. At each end of the machine, the upper ends of the corner posts are connected by a channel beam, B¹, bolted to the corner posts; and at each end of the machine, the corner posts are similarly joined by a horizontal channel beam, B², having a horizontal flange resting on the upper ends of the corner posts while the other flange extends

downward flatwise against the outer faces of the corner posts. Said beams are suitably bolted to the corner posts. At each side of the machine, near the lower ends of the corner posts, a horizontal channel beam, B³, joins said corner posts, said beam being bolted to said posts. The members thus far described constitute the frame of the machine, excepting that the bridge pieces to be described further on may also be regarded as frame members.

The plates or platens are horizontal and are of two kinds, active and idle. The active platens are directly engaged and raised and lowered by lifting mechanism. The idle platens are not engaged by the lifting mechanism, but are engaged only by the active platens.

C, C are the idle platens. These alternate in position with the active platens, D, D.

The active platens are wide enough to make their front and rear edges meet the front and rear flanges of the corner posts, A. Thus the platens are held against forward or backward movement. A bar, C¹, extends across each end of each platen, C, and is secured thereto by bolts, C², extending through the bar into the platen. The end of each of said bars extends through an upright slot, A¹, in the front and rear flanges of the corner posts. Normally said bars rest in the lower part of the slots, the platen being held at rest in this manner. Each slot extends above the bar, C¹, far enough to allow the lifting of the platen through a short range.

The bars, C¹, can not move sidewise in the slots, A¹. Hence said bars hold the platens, C, against endwise movement, while the front and rear flanges of the corner posts, A, hold said platens against forward or backward movement.

The active platens, D, D are of the same width as the idle platens, C, C, and the platens, D, D, are long enough to extend against the end flanges of the corner posts, A, A. Thus the active platens are held against sidewise movement and against endwise movement. On each end of each platen, D, near each corner post, is a horizontal

wrist, D^1 , which is rigid on the platen. Surrounding each such wrist is an anti-friction roller, D^2 , which is adapted to engage the flange, F^2 , of a cam, F , which surrounds and is fixed on the adjacent upper shaft, E . Each of said shafts has its lower end resting in a bearing, E^1 , while its upper end extends through a bearing, E^3 . Immediately above the bearing, E^3 , 10 each shaft has an annular shoulder or ring, E^2 , which rests on the adjacent bearing, E^1 . On each cam, F , the flange, F^2 , is directed upward and is concentric with the shaft. Said flange varies in height, so that 15 during the rotation of the shaft and the cam, the part of the flange passing beneath the roller, D^2 , will vary in height. By this means, the roller, D^2 , the wrist, D^1 , and the platen are lifted. The four cams 20 which are opposite the same platen, D , are set on their shafts to simultaneously present the engaging parts of the flanges in the same horizontal plane, in order that the platen may, during its movement, be kept 25 parallel to a horizontal plane.

The shafts, E , and the cams, F , are to be rotated continuously or at intervals as may be desired.

On the upper end of each of said shafts is 30 fixed a worm wheel, E^4 , which is engaged by a worm, G , fixed on a horizontal shaft, G^1 , resting in bearings, G^2 , seated on the upper end beams, B^2 , of the frame of the machine. Such a shaft is located at each end of the 35 machine. At the middle of each of said shafts is a worm wheel, G^3 , which is fixed to said shaft and is engaged by a worm, H , on the cross shaft, H^1 , which rests in bearings, H^2 , formed on the transverse horizontal bridge pieces H^3 , which have their ends 40 resting on and bolted to the upper front and rear horizontal beams, B^2 . Between the bearings, H^2 , a pulley, I , surrounds and is fixed to the shaft, H . Power is to be applied 45 to said pulley by a belt.

When said pulley is rotated, the shafts, H^1 , G^1 , and E , are rotated. By the rotation of the shafts, E , the cams, F , are rotated. The rotation of the cams causes the lifting and lowering of the active platens, D . When the highest parts of the flanges, F^2 , of the cams pass under the rollers, D^2 , of a platen, D , that platen is lifted high enough to bear 50 against the next upper idle platen, C , and lift that platen from its seats in the slots, A^1 , of the corner posts. When the lowest parts of the flanges, F^2 , are passing beneath the rollers, D^2 , the platen is allowed to descend until it bears upon the next lower idle 55 platen and rests thereon or on the material placed between said platens. During the continuation of the rotation of those four cams, the higher parts of the cams again come under the rollers and lift them and 60 their platen until said platen again bears 65

against and lifts the next upper platen. This action continues as long as these cams are being rotated.

The four cams of any platen may be set into their radial relation on the shafts, E , without reference to the radial setting of the cams which are associated with other platens. If so desired, all the cams on the four shafts may be set in the same radial relation so that all the cams will lift all the 75 platens, D , simultaneously. But that would involve the lifting of all the active platens and all but the lower of the idle platens at the same time, thus making an accumulation of load equaling the weight of all the 80 platens, D , and all the platens, C , excepting the lowest and the material at the time between the platens, except the lowest. The load to be thus lifted can be reduced by distributing or dividing the radial arrangement of the cams on the shafts E . Any such division will divide the load to be lifted. The drawings illustrate a complete division 85 of the arrangement of the cams, the highest part of the flanges of the several groups of cams being turned progressively to divide the lifting of the platens during one rotation of the shaft into as many time intervals as there are cams on one shaft. Thus the active cams are brought successively to the 90 upper limit of their range of movement. By this means we attain the minimum of load to be lifted at one time.

It will be understood that the sheet-form material to be pressed is to be placed into the 100 space between any two platens when those platens are separated from each other. It will also be understood that the material may be left between any two platens until those platens have been separated and brought into engagement as often as needed for the treatment of said material.

If it is desired to have the plates warm or hot during operation, they may be made 110 hollow or otherwise formed for conducting steam or hot water through them. The drawings show ports, J , J , on the ends of the platens for the connection of tubing through which hot water or steam may be delivered 115 into and exhausted from the platens in the manner already known in this art.

It is to be noted that the cams and the rollers are not coupled nor otherwise permanently engaged to each other, that the cams are free from the rollers, D^2 ; that they engage the rollers only by moving upward and bearing against the rollers. That arrangement allows the active platens to move downward and rest on the next lower idle platens, 120 while the flanges, F^2 , separate from the rollers and continue downward movement.

I claim as my invention.

1. In an apparatus of the kind described, the combination with a supporting frame, of 125 two groups of superposed horizontal plat-

ens, and means for lifting the platens of one or said groups at different times, substantially as described.

2. In an apparatus of the kind described, 5 the combination with a supporting frame, of two groups of superposed horizontal platens, and means for lifting the platens of one of said groups serially, substantially as described.

10 3. In an apparatus of the kind described, the combination with a supporting frame, of two groups of superposed horizontal platens, and cams for lifting the platens of one of said groups at different times, substantially as described.

15 4. In an apparatus of the kind described, the combination with a supporting frame, of two groups of superposed horizontal platens, and cams for lifting the platens of one 20 of said groups serially, substantially as described.

25 5. In an apparatus of the kind described, the combination with a supporting frame, of a group of superposed horizontal platens seated independently of each other in the frame, a second group of platens alternating with the platens of the first group, and means for lifting the platens of the second group at different times against platens of 30 the first group, substantially as described.

35 6. In an apparatus of the kind described, the combination with a supporting frame, of a group of superposed horizontal platens seated in the frame, a second group of platens alternating with the platens of the first group, and means for lifting the platens of the second group serially, substantially as described.

40 7. In an apparatus of the kind described, the combination with a supporting frame, of a group of superposed horizontal platens seated in the frame, a second group of platens alternating with the platens of the first group, and cams for lifting the platens of the second group at different times against platens of the first group, substantially as described.

45 8. In an apparatus of the kind described, the combination with a supporting frame, of a group of superposed horizontal platens seated in the frame, a second group of platens alternating with the platens of the first group, and cams for lifting the platens of the second group serially, substantially as described.

50 9. In an apparatus of the kind described, the combination with a supporting frame, of a group of superposed horizontal platens, a second group of platens alternating with the platens of the first group, and cams for lifting the platens of the second group at different times, substantially as described.

55 10. In an apparatus of the kind described, the combination with a supporting frame, of a group of superposed horizontal platens, a

second group of horizontal platens alternating with the platens of the first group, and means for at different times lifting the platens of the second group to bear against the next higher platens of the first group and to descend and rest upon the next lower platens of the first group, substantially as described.

11. In an apparatus of the kind described, 75 the combination with a supporting frame, of a group of superposed horizontal platens, a second group of horizontal platens alternating with the platens of the first group, and cams for at different times lifting the platens of the second group to bear against 80 the next higher platens of the first group and to descend to rest upon the next lower platens of the first group, substantially as described.

12. In an apparatus of the kind described, 85 the combination with a supporting frame, of a group of superposed horizontal platens having extensions on their edges, and lifting means operating to engage said extensions singly for the single lifting of said platens, 90 substantially as described.

13. In an apparatus of the kind described, the combination with a supporting frame, of a group of superposed horizontal platens having extensions on their edges, and lifting 95 means operating to engage said extensions serially for the serial lifting of said platens, substantially as described.

14. In an apparatus of the kind described, the combination with a supporting frame, of 100 a group of superposed horizontal platens having rollers on their edges, and lifting means operating to engage said rollers singly for the single lifting of said platens, 105 substantially as described.

15. In an apparatus of the kind described, the combination with a supporting frame, of a group of superposed horizontal platens having rollers on their edges, and lifting 110 means operating to engage said rollers serially for the serial lifting of said platens, substantially as described.

16. In an apparatus of the kind described, the combination with a supporting frame, of a group of superposed horizontal platens, 115 and upright shafts in operative relation with said platens for raising said platens, substantially as described.

17. In an apparatus of the kind described, the combination with a supporting frame, 120 of a group of superposed horizontal platens, and upright shafts in operative relation with said platens for raising said platens singly, substantially as described.

18. In an apparatus of the kind described, 125 the combination with a supporting frame, of a group of superposed horizontal platens, and upright shafts in operative relation with said platens for raising said platens serially, substantially as described. 130

19. In an apparatus of the kind described, the combination with a supporting frame, of a group of superposed horizontal platens, and cam shafts in operative relation with 5 said platens for lifting said platens, substantially as described. having extensions at their edges, upright cam shafts, and cams supported on said shafts and set in different radial positions to adapt them to engage said extensions and lift said platens at different times, substantially as 70 described.
20. In an apparatus of the kind described, the combination with a supporting frame, of a group of superposed horizontal platens, 10 and cam shafts in operative relation with said platens for lifting said platens singly, substantially as described. 75
21. In an apparatus of the kind described, the combination with a supporting frame, 15 of a group of superposed horizontal platens, and cam shafts in operative relation with said platens for lifting said platens serially, substantially as described. 80
22. In an apparatus of the kind described, 20 the combination with a supporting frame, of a group of superposed horizontal platens, a second group of horizontal platens alternating with the platens of the first group, and cam shafts in operative relation with 25 the platens of the second group for lifting 85 said platens, substantially as described. 90
23. In an apparatus of the kind described, the combination with a supporting frame, 30 of a group of superposed horizontal platens, a second group of horizontal platens alternating with the platens of the first group, and cam shafts in operative relation with the platens of the second group for lifting 35 said platens singly, substantially as 95 described. 100
24. In an apparatus of the kind described, the combination with a supporting frame, of a group of superposed horizontal platens, 40 a second group of horizontal platens alternating with the platens of the first group, and cam shafts in operative relation with the platens of the second group for lifting 45 said platens serially, substantially as described. 105
25. In an apparatus of the kind described, 50 the combination with a supporting frame, of a group of superposed horizontal platens, and upright cam shafts in operative relation with said platens for lifting said platens, substantially as described. 110
26. In an apparatus of the kind described, the combination with a supporting frame, of a group of superposed horizontal platens, and upright cam shafts in operative relation 55 with said platens for lifting said platens singly, substantially as described. 115
27. In an apparatus of the kind described, the combination with a supporting frame, of a group of superposed horizontal platens, 60 and upright cam shafts in operative relation with said platens for lifting said platens serially, substantially as described. 120
28. In an apparatus of the kind described, the combination with a supporting frame, of 65 a group of superposed horizontal platens 125
- having extensions at their edges, upright cam shafts, and cams supported on said shafts and set in different radial positions to adapt them to engage said extensions and lift said platens at different times, substantially as 70 described.
29. In an apparatus of the kind described, the combination with a supporting frame, of a group of superposed horizontal platens, pairs of upright shafts placed at opposite 75 edges of the platens and in operative relation with the platens for lifting the platens, means connecting said shafts in pairs, and driving means for driving said connecting means in unison, substantially as described. 80
30. In an apparatus of the kind described, the combination with a supporting frame, of a group of superposed horizontal platens, pairs of upright shafts placed at opposite 85 edges of the platens and in operative relation with the platens for lifting the platens, two cross shafts, one geared to one and the other geared to the other pair of upright shafts, and driving means connecting the two cross shafts for driving the cross shafts 90 in unison, substantially as described. 95
31. In an apparatus of the kind described, the combination with a supporting frame, of a group of superposed horizontal platens, two horizontal shafts located adjacent opposite borders of said group, and means placing said shafts into operative relation with said platens for lifting said platens, substantially as described. 100
32. In an apparatus of the kind described, the combination with a supporting frame, of a group of superposed horizontal platens, two horizontal shafts located adjacent opposite borders of said group, and means placing said shafts into operative relation 105 with said platens for lifting said platens singly, substantially as described. 110
33. In an apparatus of the kind described, the combination with a supporting frame, of a group of superposed horizontal platens, two horizontal shafts located adjacent opposite borders of said group, and means placing said shafts into operative relation with said platens for lifting said platens serially, substantially as described. 115
34. In an apparatus of the kind described, the combination with a supporting frame, of a group of superposed horizontal platens, two horizontal shafts located adjacent opposite borders of said group, and means comprising cams placing said shafts into operative relation with said platens for lifting said platens, substantially as described. 120
35. In an apparatus of the kind described, the combination with a supporting frame, of a group of superposed horizontal platens, two horizontal shafts located adjacent opposite borders of said group, and means comprising cams placing said shafts into operative relation with said platens for lifting 125 130

said platens singly, substantially as described.

36. In an apparatus of the kind described, the combination with a supporting frame, of a group of superposed horizontal platens, two horizontal shafts located adjacent opposite borders of said group, and means comprising cams placing said shafts into opera-

tive relation with said platens for lifting said platens serially, substantially as described. 10

In testimony whereof I have signed my name, this 10th day of April, in the year one thousand nine hundred and twenty-two.

CYRUS KEHR.
